UNITED STATES PATENT OFFICE.

LOUIS FLICKER, OF SAN FRANCISCO, CALIFORNIA.

HAT-BLOCKING APPARATUS.

1,156,356.

Specification of Letters Patent. Patented Oct. 12, 1915.

Application filed August 24, 1914. Serial No. 858,569.

To all whom it may concern:

Be it known that I, LOUIS FLICKER, a citizen of the United States, residing in the city and county of San Francisco, State of California, have invented a new and useful Improvement in Hat-Blocking Apparatus, of which the following is a specification.

My invention relates to improvement in hat blocking apparatus as disclosed in Patent No. 896,370, patented August 18th, 1908, and the objects of the present improvement are, first, to provide a detachable super-imposed structure for forming the brims of straw hats; second to provide means for imparting a whirling motion to the steam so that all portions of a hat placed in the receptacle provided therefor will be subjected to an equal amount of steam; and third, to provide improved means whereby the steam from the boiler will be automatically turned on when the receptacle provided for the hats is pressed downward and wherein the steam is automatically shut off when the pressure on the receptacle is released.

A further object of the present improvement is to provide means whereby the boiler may be re-filled through the hat receptacle.

I accomplish these several objects by means of the device shown in the drawings forming a part of the present specification wherein like characters of reference are used to designate similar parts throughout the said specification and drawings, and in which—

Figure 1 is a vertical sectional view of my improved apparatus disclosing the manner in which the steaming receptacle is operatively connected to the valve through which steam is supplied to the said receptacle; also the super-imposed drum and irons for use in forming hat brims for straw hats. Fig. 2 is an enlarged vertical sectional view of the steaming receptacle. Fig. 3 is a plan view of the super structure from the boiler and disclosing a straw hat thereon with the irons in place. Fig. 4 is a vertical sectional view taken on line X—X of Fig. 3 of the drawings in the direction indicated by the arrow. Fig. 5 is a plan view of the steaming receptacle disclosing the inclined nozzles thereon, and Fig. 6 is a detailed sectional view of the automatic valve through which steam is supplied to the steaming receptacle.

Referring to the drawings, the numeral 1 is used to designate a steam boiler supported by means of suitable legs 2 and adapted to

be heated by means of a suitable burner 3. The boiler 1 is provided with a water gage 4 and a suitable drain pipe 5. A steaming receptacle 6 is provided, which is similar in construction and operation to the larger one, hereinafter more fully described.

The boiler 1 is provided with a super-imposed drum 7 having a flat top 8 on which the work of re-shaping brims or hats is performed in conjunction with the arcuate irons 9 and for heating the said hats prior to the drying and re-shaping operation.

On the side of the boiler 1 opposite the steaming receptacle 6 is a valve casing 12 having an enlarged bore 14 which communicates with the interior of the boiler 1 by means of the aperture 15. The bore 14 is provided with a reduced portion 16 and a valve seat 17 to seat between the said bore 14 and reduced portion 16 thereof.

A hollow stem 18 having apertures 19 therein and a valve 20 on the lower end thereof is slidably mounted within the reduced portion 16 of the bore 14 and a spring 21 is interposed between the valve 20 and the lower portion of the bore 14, so that the tension of the said spring 21 will assist the steam pressure within the bore 14 and tend to retain the said valve 20 of the hollow stem 18 on the seat 17 and thus prevent the steam from escaping through the hollow stem 18 and through a plurality of downwardly inclined nozzles 22 secured to the top of the hollow stem 18 and within a steaming receptacle 23 which is also secured to and adapted to move with the hollow stem 18.

The receptacle 23 is provided with a drain pipe 24 having a valve 25, the purpose of which will hereinafter be more fully described. The receptacle 23 is also provided with an inner cloth lining 26 which is adapted to catch the condensed particles of steam and allow the same to fall downwardly to the bottom of the receptacle without coming in contact with the hat placed therein. By removing the fitting containing the inclined nozzles and closing the valve 25 in the drain pipe 24 of the receptacle 23, the said receptacle 23 may be used as a means for filling the boiler 1 by depressing the said receptacle 23 until the apertures 19 in the hollow stem 18 pass below the seat 17, so that water may flow through the said apertures and into the boiler 1.

When in position in the receptacle 23, the brim of a hat hangs over the rim of the

said receptacle, as shown in dotted lines in Fig. 1 of the drawings. From this figure, it will be noted that the crown of a hat is in a position to be thoroughly heated and steamed from the vapor emerging from the inclined nozzles 22. In order to steam the hat, it is placed in the receptacle 23 and the said receptacle pressed downward against the tension of the spring 21 until the apertures 19 of the hollow stem 18 are below the seat 17 when the steam will flow through the said apertures 19 and hollow stem 18 and through the downwardly inclined nozzles 22. As the steam emerges from the nozzles, the 15 inclinations of the said nozzles direct the steam against the concaved bottom 30 of the receptacle 23 and is thus given a whirling motion so that the steam will travel around the interior surface of the receptacle 23. 20 In this manner, an equal amount of steam will be delivered to all portions of the crown of a hat.

It is evident that the amount of steam delivered to the receptacle 23 is in direct proportion to the amount of downward pressure on the said receptacle 23, so that the amount of steam delivered to the said receptacle will be easily and readily regulated without the manipulation of a separate 30 valve.

In forming the rim of a straw or similar hat, the same is placed upon the flat top 8 of the super-imposed drum 7 and the arcuate irons 9 are placed upon the rim of the 35 hat. In this manner, the heat from the boiler will in turn heat the top 8 of the drum 7 and the heat will be communicated to the rim of the hat which is held in proper position by the weight of the arcuate irons 9. 40 When the drum 7 is not being used, the irons 9 are left on the top thereof, so that the same will always be hot and ready for instant use.

It is obvious from the foregoing that I 45 have provided improved means whereby the crowns of hats may be thoroughly renovated and re-shaped without the necessity of softening the brims thereof. It is also obvious that I have provided improved means for 50 distributing the steam equally throughout the interior of the steaming receptacle 23, so that all parts of the crown of a hat will receive the same amount of dry steam. I have also provided improved means for automatical

admitting steam to the receptacle 23 when the same is pressed downward and for automatically shutting off the steam when the said downward pressure has been released.

Having thus described my invention what 60 I claim as new and desire to secure by Letters Patent is:

1. In a device of the character described, a steam boiler; a steaming receptacle connected to the said boiler, the top of the receptacle being open; an inner fabric lining for the walls of the said receptacle; and means operatively connected to the receptacle and the boiler and arranged to deliver steam into the said receptacle when the same 70 is pressed downward.

2. In a device of the character described, a steam boiler; a valve casing secured to the side of and connected with the steam boiler and having a vertically disposed bore therein with a reduced portion and a seat thereto; a hollow stem having apertures and a valve upon the lower end thereof slidably mounted in the reduced portion of the bore; means for normally retaining the valve on the seat; 80 a steaming receptacle secured to the top of the hollow stem; and means secured to the top of the hollow stem and within the receptacle and arranged to impart a whirling motion to the steam emanating from the said 85 stem.

3. In a device of the character described; a steam boiler; a valve casing secured to the side of and connected with the steam boiler and having a vertically disposed bore therein with a reduced portion and a seat thereto; a hollow stem having apertures and a valve upon the lower end thereof slidably mounted in the reduced portion of the bore; means for normally retaining the valve on the seat; 90 a steaming receptacle secured to the top of the hollow stem; a plurality of inclined nozzles secured to the hollow stem and within the receptacle and arranged to impart a whirling motion to steam emanating from the said nozzles. 100

In witness whereof I hereunto set my signature in the presence of two subscribing witnesses.

LOUIS FLICKER.
